RALPH S. TYLER, OF CLEVELAND HEIGHTS, OHIO, ASSIGNOR TO THE CHANDLER & PRICE COMPANY, OF CLEVELAND, OHIO, A CORPORATION OF OHIO.

THROW-OFF MECHANISM FOR PRINTING PRESSES.

Application filed February 12, 1925. Serial No. 8,716.

The use of throw-off mechanism in platen printing presses or presses of the so-called Gordon type is quite familiar and well understood, the object of such mechanism being so to shift the position of the bed that without interrupting its oscillation, or, in other words, stopping the press, the form carried by said bed will nevertheless be prevented from contacting with the platen. 10 This shifting is ordinarily accomplished by eccentrically connecting the bed operating means with the ends of the so-called back shaft which is suitably journaled in the bed, such shaft being rockable so as to vary 15 in effect the throw of said operating means.

In the operation of a press, it is necessary to use such throw-off mechanism whenever the sheet on the platen slips or is improperly adjusted, as well as on other occasions, 20 and it accordingly becomes important that said mechanism be not only simple in construction but so designed as not to interfere with the normal operation of the press. Various difficulties known in the trade as 25 "jumping" and "winking" are as a matter of fact attributable to the present construction of throw-off mechanism, being occasioned by a slight rocking movement of the aforesaid back shaft even when the throw-off mechanism is in its inoperative position.

One object of the present invention, accordingly, is to provide a mechanism that will insure against such incidental and undesired oscillation of the back shaft while at the same time said shaft may be easily rocked whenever it is desired to throw the bed off and avoid contact of the form with the platen. To the accomplishment of the foregoing and related ends, the invention, then, consists of the means hereinafter fully described and particularly pointed out in the claims, the annexed drawing and the following description setting forth in detail 40 certain mechanism embodying the invention, such disclosed means constituting, however, but one of various mechanical forms in

which the principle of the invention may be used.

In said annexed drawing:—

Fig. 1 is a side elevation of a platen or Gordon press equipped with my present improved throw-off mechanism; and Figs. 2 and 3 are sections of details of such mechanism taken on the planes indicated by the lines 2—2 and 3—3, Fig. 1, respectively.

The press is of familiar construction, comprising a platen 1, suitably supported on a frame 2, and an oscillatory form-carrying bed 3 that is swung toward and away from said platen through the medium of cranks 4 and connecting rods or side arms 5. The cranks 4, of which there are two, one on each side of the press, are in fact pins that project outwardly from disks 6 mounted on the corresponding ends of the front shaft 7, and the rear ends of the arms 5 are connected to the bed 3, as hereinbefore indicated, through the medium of outwardly projecting eccentric pins 8 on the corresponding ends of back shaft 9. The ink distributing disk 10, form 11 and form rollers 12 require no special description.

The throw-off mechanism of present interest, as has also been hereinbefore indicated, is designed to rock the back shaft 9 so as to shift the position of the eccentric pins 8 and thereby change the position of bed 3 with form 11 relatively to crank pins 4. In Fig. 1, the parts as shown in full lines 75 occupy the on position in which the form will contact with the platen, while the dotted position of parts indicates the platen in off position.

The throw-off mechanism comprises a 80 handled lever 15 that is oscillatorily attached at an intermediate point 16 to one side of the frame 2. Similarly oscillatorily attached to such frame side at a point 17, located rearwardly with respect to point 16, is 85 a double arm lever 18, the upper end of which is connected with the lower end of lever 15 by means of a link 19. The lower end of said lever 18 has sliding pivotal con-

- connection with one arm of a bell crank 20, the other arm of which is connected by means of a long link 21 with a lever arm 22 fixed to the adjacent end of back shaft 9 and radially projecting therefrom. The upper end of said link 21 is curved so as to clear the shaft in the on position of the latter, illustrated as aforesaid in full lines in Fig. 1, the movement imparted to said shaft being approximately through an arc of 90 degrees and in a counter-clockwise direction in rocking the shaft from such on to its off position.
- For the purpose of securing the slideable pivotal connection between the lower end of lever 18 and the one arm of the bell crank 20, such end is provided with a stud 23 that engages with an elongated slot 24 in said bell crank arm. Said bell crank may accordingly be rocked through substantially the same angle as back shaft 9, the pin 23 traveling in and then out along slot 24 so that at the initiation of the rocking movement, whether from off to on position of the parts, or vice versa, the pin always occupies its outermost position. It will further be noted that, as clearly shown in Fig. 2, the bell crank is oscillatory supported upon the same axis, in fact upon the same shaft or rod 25 whereon bed 3 is oscillatory mounted! As a result of this feature of construction, there will be substantially no movement imparted to the link and lever system that connects said bell crank with back shaft 9 relatively to the bed itself when the latter is oscillated with said system in on position. In other words, the back shaft is held against any slight rocking movement in its bearings in this position of the parts with the result that the eccentric pins are for all intents and purposes fixed in the bed, thus insuring smooth, easy to and fro movement of the latter when the press is running normally.
- It will further be noted that in the on position of the parts, the arm of bell crank 20, wherewith link 21 is connected, is swung far enough forwardly to bring said arm and the point of pivotal connection between the same and said link substantially in a line joining the center of said bell-crank and the end of arm 22. This makes for rigidity, any tendency of the back shaft to roll being resisted by a straight line pull on the parts in question. Finally, by reason of the sliding pivotal connection between lever 18 and the other arm of the bell-crank, the latter is effectively locked in both its off and its on position, the lever being arranged to swing through an arc (slightly over 90°) sufficient to insure against accidental breaking of the joint inwardly.
- Other modes of applying the principle of my invention may be employed instead of the one explained, change being made as

regards the mechanism herein disclosed, provided the means stated by any of the following claims or the equivalent of such stated means be employed.

I therefore particularly point out and distinctly claim as my invention:—

1. In a platen printing press, the combination with the oscillatory bed, a back-shaft journaled in said bed and side-arms eccentrically connected with said shaft; of means for rocking said shaft in order to prevent the making of an impression, said means including an oscillatory lever-member mounted to swing on an axis substantially coaxial with the axis of said bed, a lever projecting from said shaft, and a link connecting said levers.

2. In a platen printing press, the combination with the oscillatory bed, a back-shaft journaled in said bed and side-arms eccentrically connected with said shaft; of means for rocking said shaft in order to prevent the making of an impression, said means including an oscillatory lever-member mounted to swing on an axis substantially coaxial with the axis of said bed, a lever projecting from said shaft, and a link connecting said levers, said link and the point of pivotal connection between the same and said first-named lever lying substantially in a line joining the axis of said lever and the end of the lever projecting from said shaft in the impression-on position of the parts.

3. In a platen printing press, the combination with the oscillatory bed, a back-shaft journaled in said bed and side-arms eccentrically connected with said shaft; of means for rocking said shaft in order to prevent the making of an impression; said means including a bell-crank oscillatory about substantially the same axis as said bed, a lever projecting from said shaft, a link connecting one arm of said bell-crank with said lever, and another lever having a sliding pivotal connection with the other arm of said bell-crank, whereby the latter may be rocked as well as locked in either limiting position.

4. In a platen printing press, the combination with the oscillatory bed, a back-shaft journaled in said bed and side-arms eccentrically connected with said shaft; of means for rocking said shaft in order to prevent the making of an impression, said means including a bell-crank oscillatory about substantially the same axis as said bed, a lever projecting from said shaft, a link connecting one arm of said bell-crank with said lever, and another lever having a pin on its end, the other arm of said bell-crank having a slot in sliding pivotal engagement with said pin.

5. In a platen printing press, the combination with the oscillatory bed, a back-shaft journaled in said bed and side-arms eccen-

trically connected with said shaft; of means for rocking said shaft in order to prevent the making of an impression, said means including a bell-crank oscillatory about substantially the same axis as said bed, a lever projecting from said shaft, a link connecting one arm of said bell-crank with said lever, a double arm lever having a pin on

one end, the other arm of said bell-crank having a slot in sliding pivotal engagement with said pin, a handled operating lever, and a link connecting the same with the other end of said double-arm lever. 10

Signed by me this 9th day of February, 1925.

RALPH S. TYLER.
